Isaac Bedichimer

UNITED STATES PATENT OFFICE.

ISAAC BEDICHIMER, OF PHILADELPHIA, PENNSYLVANIA.

DESIGN FOR A BADGE.

SPECIFICATION forming part of Design No. 29,811, dated December 20, 1898.

Application filed November 4, 1898. Serial No. 695,456. Term of patent 3½ years.

To all whom it may concern:

Be it known that I, ISAAC BEDICHIMER, of the city of Philadelphia, in the county of Philadelphia, State of Pennsylvania, have invented and produced a new and original Design for Badges, of which the following is a specification, reference being had to the accompanying drawing, forming part hereof.

My design for a badge consists of a female figure the face of which is polished and the dress drapery of which is to be in varying or contrasting shades. The figure is represented as sitting on an enameled crescent, which crescent is itself supported by an Arabian

simitar running across the back thereof, showing the hilt of the sword at one end of the crescent and the point of it at the other.

What I claim is—

The design for a badge as herein described and shown.

In testimony that I claim the design above set forth I affix my signature in presence of two witnesses.

ISAAC BEDICHIMER.

Witnesses:

LEO BELMONT,
HARRY L. PARKINSON.
